TELEPHONE INSTRUMENT

Harold C. Pye, Oak Park, Ill., assignor to Associated Electric Laboratories, Inc., Chicago, Ill., a corporation of Delaware

Application February 6, 1937, Serial No. 124,425

6 Claims. (Cl. 179—103)

The present invention relates to telephone instruments and more particularly to the hand set type of instrument employed with the cradle type of telephone.

Various forms of instruments of the general type noted are commercially available, all of which operate in a more or less satisfactory manner insofar as their electrical and acoustical characteristics are concerned. In at least one conventional form of hand set now widely used, all of the exposed parts, comprising the handle, the mouth piece and the ear piece, are constructed of moulded insulating material such as that sold under the trade-name "Bakelite", the various terminal members and the conductors interconnecting the same being embedded in the moulded compound. This form of instrument, while desirable from the viewpoint of insulating the user from the electrical circuits of the set, possesses various structural defects and presents certain definite manufacturing difficulties. Thus, in the usual instrument of the specific type mentioned, the cord terminal terminates at one end of the set and the conductors extending therefrom to the instrument cell at the other end are bare conductors embedded in the moulded handle, which conductors are susceptible of becoming entangled and electrically interconnected during the moulding process, whereby the finished product is necessarily defective and must be rejected. A further structural deficiency resides in the insubstantial supporting of the transmitter and receiver assemblies or cells, thereby detracting from the ruggedness of the instrument. Another characteristic feature which further detracts from the ruggedness pertains to the "Bakelite" screw threads by which the ear and mouth pieces are conventionally secured to the cups individually housing the receiver and transmitter cells. This method of attaching the ear and mouth pieces to the respectively associated cups also lends itself to ready disassembly of the instrument thus enabling unskilled persons to take the instrument apart and expose the delicate working parts to dirt, moisture, and improper handling. Dirt and moisture, more specifically the latter, also have ready access to the transmitter cell diaphragm through the sound transmission holes normally provided in the mouth piece and in other parts interposed between this piece and the transmitter cell diaphragm. The resulting accumulation of dirt and moisture on the transmitter diaphragm may adversely affect the frequency response of the latter to the acoustical

vibrations causing its operation, thereby detracting from the transmission fidelity.

It is an object of the present invention, therefore, to provide a telephone hand set comprising transmitter and receiver cups, self-contained transmitter and receiver cells arranged in the corresponding cups, mouth and ear pieces associated with the corresponding cups, and improved arrangements for securing each of the cells in its corresponding cup independently of the mouth or ear piece associated therewith.

It is another object of the invention to provide an improved telephone instrument of the general type noted which is of simple and economical construction and is free of the various mechanical deficiencies outlined above.

More specifically, it is an object of the invention to provide an improved telephone hand set which may easily be manufactured in production quantities with a minimum number of defective instruments and which has one or more of the following characteristics: rugged construction, protection against dirt and moisture, and protection against unauthorized disassembly by unskilled persons.

In brief, the objects as generally set forth above are attained in accordance with the present invention by providing various structural improvements for an instrument of the general type noted and comprising transmitter and receiver cups constructed of insulating material and individually including contact members, together with self-contained transmitter and receiver cells including contact members for individually engaging the corresponding contact members of the corresponding cup. The usual ear and mouth pieces or members are also provided which similarly are constructed of insulating material. These improvements relate in part to the method and means whereby the instrument is assembled. Thus, each of the transmitter and receiver cells is provided with means for securing it to the corresponding cup independently of the corresponding ear or mouth piece, additional means being employed for securing the corresponding pieces to their associated cells. The arrangement is such that each cup, in cooperation with its associated ear or mouth piece, completely surrounds the associated cell and these two elements are locked against relative movement therebetween when fully assembled. Each of the two means for respectively securing the ear and mouth pieces to their associated cells is constructed so that it alone can be actuated to remove the piece or member secured thereby. These securing means

in combination with the locking means referred to above, fully protect an assembled instrument from unauthorized disassembly by unskilled persons. Provision is also made for protecting the working parts of the transmitter, and particularly the transmitter diaphragm, against moisture and dirt which normally enter through the sound transmission holes or apertures of the mouth piece. This is accomplished by offsetting the holes in the mouth piece with respect to the holes in the front supporting member of the transmitter cell so that no direct path exists between the mouth piece opening and the transmitter diaphragm. The means for interconnecting the contact members of the two cups comprises conductors embedded in the moulded handle, at least a portion of which have insulating material thereon so that during the process of manufacture there is no possibility of electrical interconnection of these conductors.

The novel features believed to be characteristic of the invention are set forth with particularity in the appended claims. The invention itself, however, both as to its organization and method of operation, together with further objects and advantages thereof will best be understood by reference to the specification taken in connection with the accompanying drawings, in which: Figure 1 is a cross-sectional view illustrating a telephone instrument of the hand set type having embodied therein the features of the present invention; Fig. 2 is a schematic view illustrating the manner of electrically interconnecting the various elements of the instrument; Fig. 3 is an exploded view illustrating the details of the receiver and the mode of assembling the various elements thereof; Fig. 4 illustrates the details of the locking means embodied in the receiver assembly; Fig. 5 is an exploded view illustrating the elements of the transmitter and their mode of assembly; and Figs. 6 to 9, inclusive, are bottom, top, and cross-sectional views respectively, illustrating the details of the receiver cell construction.

Referring now more particularly to Fig. 1 of the drawings, there is shown a telephone instrument of the hand set type having embodied therein the various features of the invention as outlined above. In brief, the instrument comprises a handle 10, having integral therewith the receiver and transmitter cups 11 and 12, respectively, which partially house the receiver and transmitter cells 13 and 14, respectively. Cooperating with the cups 11 and 12 completely to surround the cells 13 and 14 are ear and mouth pieces 15 and 16, respectively. The ear and mouth pieces or members 15 and 16 and the integral handle 10 and cups 11 and 12 are constructed of insulating material, preferably consisting of a phenol plastic compound such as "Bakelite". The mouth piece or member 16 comprises a cup-shaped portion which is adapted to engage at its outer edge the edge of the cup 12, and is provided with spaced apart sound transmission holes 17 arranged to form a circle in the bottom portion of the cup in the manner illustrated.

The transmitter cell 14 may be of any desired type although preferably the moving parts thereof are constructed and arranged in the manner illustrated and described in applicant's co-pending application Serial No. 40,738, filed September 15, 1935. In brief, the cell comprises a pair of supporting members 18 and 19 preferably consisting of a light weight aluminum alloy, and are provided with interengaging threads 20 and 21

for assembling the cell. The member 18 is provided with spaced apart sound transmission holes or openings 22 which are arranged on a circle of smaller diameter than the circle of the holes 17 in the mouth piece 16, the adjacent surfaces 23 and 24 of the members 18 and the mouth piece 16 being spaced apart by means of a thin washer 25 of soft rubber or other suitable material, to permit sound waves to travel through the two sets of openings 17 and 22 to the diaphragm of the cell. By offsetting the two sets of holes 17 and 22 in the manner described, dirt and moisture, more particularly the latter passing through the outer set of openings 17, are intercepted by the solid outer surface 23 of the member 18 and do not enter the openings 22 leading to the transmitter diaphragm. Thus, the delicate parts of the transmitter's moving system are protected from foreign matter.

As described in the above referred to co-pending application, the moving system of the transmitter cell 14 comprises a conically-shaped main diaphragm 26 having a relatively wide flange around its outer edge which is clamped between adjacent surfaces of the supporting members 18 and 19 in the manner shown, and a secondary diaphragm 27 in the form of a conical ring having an opening in the center thereof. A dome-shaped cup 28 extends through this opening and is provided with a flange which overlaps the edge of the opening in the secondary diaphragm 27 and, in conjunction with a rivet 29, holds the diaphragm assembly together. A ring-shaped electrode 30 constructed of carbon is fastened to the flanged portion of the cup 28 in any suitable manner to move therewith, and opposite this moving electrode there is provided a second carbon electrode 31 of the same shape which is rigidly mounted on a second dome-shaped cup 32. The latter cup is, in turn, rigidly fastened to the housing or supporting member 19 by means of a threaded ring 33, being electrically insulated therefrom by means of ring-shaped insulating washers 34 and an insulating cylindrical ring 35. Between the adjacent edges of the carbon ring electrodes 30 and 31 there is cemented a flexible paper bellows 36 of circular shape which functions to confine the granular carbon in the cell formed by the two cups 28 and 32. This bellows may be attached by gluing the edges thereof to the respective electrode surfaces. The chamber as thus formed by the two cups 28 and 32 is provided with an opening whereby it may be filled with granulated carbon material after which the opening may be plugged by means of a contact member 37.

The moving system of the transmitter cell as briefly described above operates, in general, in the manner of conventional transmitter cells of similar construction. However, the cell has certain operating advantages, resulting from the features described, which are designed to improve the frequency response characteristic and thereby to enhance the fidelity of transmission over the range of frequencies ordinarily encountered in audible conversation. Since the general mode of operation of a transmitter cell of the general type shown is well understood and the details of the moving system and the operating features thereof form no part of the present invention, a detailed description thereof is omitted in the interests of simplicity.

In accordance with conventional practice, the contact members for terminating the cord conductors of the instrument are located at the 75

transmitter end of the hand set and comprise metal inserts, two of which are shown at 38 and 39, partially embedded in the moulded "Bakelite" forming the cup 12. The insert 39 is connected by means of a spring contact piece 40 to the contact member 37 which forms the plug for the cup 32. A third contact member in the form of an annular ring 41 threaded along its outer surface is partially embedded in the "Bakelite" forming the mouth of the cup 12 and is of such a diameter that the threads of the exposed portion thereof engage the threads 20 along the inner surface of the member 18 to secure the cell 14 in its mounted position.

15 The last-mentioned annular contact member 41 is connected by means of an insulated conductor 42 embedded in the handle 10 to a contact member 43 at the receiver end of the set, which member is connected through a contact spring 44 to one of the terminals of the receiver cell 13. The contact member 43, together with a second contact member 45 in the form of a cylindrical ring, are partially embedded in the "Bakelite" forming the bottom of the receiver cup 11 and the latter 25 contact member is arranged to be connected to a second terminal of the receiver cell 13 by means of a contact spring 46 mounted on the bottom of the cell.

The receiver cell 13 comprises, in general, a 30 pair of supporting members 47 and 48 preferably of a light weight non-magnetic conducting material such as an aluminum alloy, the former of which is provided with a cylindrical flange 49 threaded along its inner surface and the latter of which is in the form of a flanged cup having threads along the outer surface of the flange which are adapted to engage with the inner threads of the flange 49 to assemble the cell. Supported within the cup-shaped member 48 35 on the bottom thereof is the magnetic field structure indicated generally at 50. This structure includes field windings 53 and 54 individually wound on corresponding pole pieces in the manner described more in detail hereinafter. A 40 thin diaphragm 51 is provided which is rigidly clamped to the upper edge of the flanged cup-shaped member 48 by means comprising the member 47 and a dished spring member 86, in the manner illustrated, and described in greater 45 detail in a later portion of the specification. It will be noted that the threads along the inner surface of the flange 49 in addition to engaging the threads of the member 48 to clamp the diaphragm 51 in place and complete the assembly 50 of the cell 13, engage the exposed threaded portion of an annular contact member 52 which is partially embedded in the "Bakelite" forming the mouth of the receiver cup 11, thereby to 55 secure the receiver cell in position within the cup independently of the ear piece 15.

Referring now more particularly to Fig. 2 of the drawings, there is illustrated in partially schematic form the manner of connecting the various contact members and circuit elements 60 of the receiver and transmitter cells to form the complete hand set network of a substation circuit. The circuit corresponds to the antiside-tone arrangement completely disclosed and described in the United States patent to Pye, No. 1,687,695, granted October 16, 1928. In conformance with the arrangement disclosed in this patent, the two field windings 53 and 54 have a common terminal, comprising the contact member 43, which is connected to one terminal of the transmitter through the conductor 42 and

the contact member 41; and independent terminals connected to the contact members 45 and 52, respectively, which are terminated at the corresponding cord terminal contact members by means comprising a pair of conductors 55 and 56, respectively. As described in the patent referred to above, the windings 53 and 54 are so proportioned relative to each other that they perform the functions of a receiver and an induction coil during the reception and transmission of signals and also form an artificial line and provide the necessary balance to secure the desired antiside-tone effect during the transmission intervals. The other contact members mounted within the transmitter cup 12 are 10 properly connected to the terminals of the transmitter cell 14 and the various conductors of the hand set cord indicated at 57 in the manner illustrated.

As indicated above, the conventional method 20 of interconnecting the various contact members is that of embedding or moulding the conductors such as 42, 55, and 56, in the handle 10 during the process of manufacture, bare conductors being used and the moulded insulating material of 25 the handle alone being depended upon to insulate the conductors one from the other. This method is not entirely satisfactory for the reason that it is difficult to maintain the conductors separated during the moulding operation and, 30 consequently, there results a high percentage of failures or defective instruments.

In accordance with one feature of the present invention this difficulty is entirely obviated by employing conductors 42, 55 and 56 for making 35 the necessary connections, at least a portion of which are pre-insulated by providing a layer of insulating material thereon. These layers for the individual enumerated conductors are indicated at 42', 55', and 56', respectively, and preferably consist of a material such, for example, as an asbestos compound, which is capable of withstanding, without deteriorating, the high temperatures necessarily involved in the moulding process. Although preferably all of the conductors are insulated in the manner shown, adequate protection against short-circuiting may be obtained if only a portion thereof are so insulated. Thus, perfectly satisfactory insulation may be obtained if only two of the three enumerated 50 conductors 42, 55 and 56 are insulated.

Referring now more particularly to Figs. 3 and 4 of the drawings, there is illustrated the method of assembling the various elements of the receiver, whereby the desirable feature of protecting this element of the hand set against unauthorized disassembly is obtained. This method comprises clamping the diaphragm 51 to the upper edge of the cupped supporting or housing member 48 by means of the supporting member 60 47 and the dished spring 86, thereby to complete the receiver cell assembly. Following this, the member 47 is screwed onto the threaded ring 52 to secure the cell 13 in place within the receiver cup 11 and to bring the associated contact members mounted on the cell and within the cup 11 into firm engagement. It is pointed out here that the inner threads of the flange 49 engage the threaded portion of the member 48 and also the exposed threaded portion of the contact member 52, and thus serve the double function of clamping the diaphragm 51 rigidly in place to provide a unitary self-contained receiver cell and rigidly to mount the cell within the receiver cup 11 independently of the ear piece or member 15. 75

Following the mounting of the receiver cell 13 in the manner described, the ear piece 15 is placed in position over the cell so that in cooperation with the cup 11 it completely surrounds the cell. 5 This piece is mounted on the cell 13, and more particularly on the member 47 by means of a flanged cap 58 having threads 59 along the shank thereof which engage threads 60 provided along the edge of a circular opening cut in the member 47. This cap is also provided with a small hexagonal sound transmission opening 62 through which the sound produced by vibration of the diaphragm 51 may be transmitted to the ear of a listener. The flange provided on the cap 15 10 58 is adapted to rest against the bottom of a groove 61 cut along the top edge of an opening in the ear piece 15 so that, when the cap is screwed into the member 47, the ear piece is firmly mounted on the cell 13.

20 As pointed out above, it is extremely desirable to provide an instrument wherein the transmitter and receiver elements cannot readily be disassembled by curious and unskilled persons. The construction of the cap 58 contributes to this 25 result in that the top thereof is flush with the face of the ear piece 15 and the element can only be unscrewed from the member 47 to remove the ear piece by employing a special tool having a hexagonal end of the proper size snugly to engage the sides of the hexagonal opening 62. It is pointed out, however, that this arrangement is alone not totally effective to prevent removal of the ear piece 15 due to the fact that sufficient friction exists between the engaging surfaces of 30 this piece and the cap 58 to enable the cap 58 to be unscrewed sufficiently to permit its removal without the use of a special tool of the form noted when the ear piece 15 is rotated relative to the receiver cup 11.

40 In accordance with a further feature of the present invention the difficulty as outlined in the preceding paragraph is obviated by providing means, in the form of inter-engaging locking means along the adjacent edges of the two 45 enumerated elements, for preventing such relative movement between the member 15 and the cup 11. As shown more particularly in Fig. 4, this locking means comprises spaced apart projections 63 interposed between grooves 64 along the inner edge of the ear piece 15 which cooperate 50 with similar grooves 65 and projections 66 alternately spaced around the outer edge of the cup 11. The interlocking action between the projections 63 and the grooves 65 prevents any substantial relative movement between the cup 11 and the ear piece 15 and thus positively prevents the cap 58 from being loosened without using a tool of the special form described.

60 As shown in Fig. 5, the method of assembling the elements of the transmitter is substantially similar to that described above in connection with the receiver assembly. Thus, the inner threads of the supporting member 18 cooperate with the threads of both the supporting member 19 and the exposed threaded portion of the contact member 41 to perform the double function of completing the transmitter cell assembly and securely mounting this cell within the transmitter cup 12 in such a position that each pair of 65 associated contact members of the cell and the cup are in firm engagement. As in the case of the receiver assembly, the mouth piece 16 is provided with spaced apart grooves indicated at 70 75 along the inner edge of its cupped portion which cooperate with projections, one of which is indicated at 68, along the upper edge of the cup 12, to prevent relative rotational movement between the mouth piece or member 16 and the cup 12. A slightly different means is provided, however, for mounting the mouth piece 16 on the transmitter cell 14. This means comprises a threaded stud 69 projecting outwardly from the supporting member 18, which stud is adapted to pass through an opening 70 in the bottom of the cupped portion of the mouth piece 16 and to have screwed thereon a cap 71 having a metal insert 72 provided with tapped threads for engaging the threads of the stud 69. This cap 71 is of a diameter not greater than the diameter of the circle tangent to the sound transmission holes or openings 17 and, with the exception of grooves 13 provided at diametrically opposite points along its sides, is of a smooth rounded contour. The grooves 13 are adapted to be engaged by the prongs of a special tool employed for the purpose of screwing the cap tightly against the outer adjacent surface of the mouth piece 16. By this method of assembly the transmitter cannot readily be taken apart except by using a special tool of the form described and consequently this portion of the hand set is also protected against unauthorized disassembly.

From the foregoing description of the transmitter and receiver assemblies it will be apparent that the individual telephone instrument cells, 30 namely, the transmitter and the receiver cells, are mounted independently of the associated ear or mouth piece. Moreover the mounting arrangement is of an extremely rugged character. It is pointed out further that the method of assembly obviates the use of "Bakelite" to "Bakelite" threads between the individual transmitter and receiver cups and their respective associated mouth and ear pieces. Also, the latter pieces receive considerable support from the cells which they individually surround. Thus, the member 47 embodied in the receiver cell 13 fits snugly within the ear piece 15 so that the shock incident to a severe blow on the ear piece is largely absorbed by the sturdier metal parts of the cell 40 45 13. For the same reason the supporting member 18 of the transmitter cell is constructed to fit snugly within the cup portion of the mouth piece 16. This additional support for the walls of the pieces 15 and 16 permits the walls thereof to be 50 made much thinner than is possible in these arrangements typical of the prior art.

Referring now to Figs. 6 to 9, inclusive, of the drawings, and more particularly to Figs. 7 and 8, there are illustrated the details of the receiver 55 cell generally described above. As shown, the magnetic field structure comprises a pair of pole pieces 74 and 75 having pole faces 76 and 77, respectively, adjacent to but separated from the diaphragms 51 by an air gap of suitable length. 60 Individually mounted on the pole pieces 74 and 75 are the windings 53 and 54, having terminals (not shown) commonly connected to the contact spring 44 and individual terminals not shown individually connected to the member 48 and the contact spring 46. The enumerated contact members are insulated from each other by insulating washers 78 and 79. Each of the pole pieces 74 and 75 includes an outwardly extending flang 70 which is provided with a portion 80 offset with respect to the plane passing through the axial centers of windings 53 and 54. Mounted on these offset portions 80 and included in the magnetic circuit of the field structure is a polarizing permanent magnet 81.

The best and improved forms of magnets suitable for use as the polarizing magnet 81 are constructed of exceedingly hard alloy steels which render the conventionally used methods of 5 mounting the same, consisting of drilling the magnet to accommodate mounting screws, costly and laborious. This difficulty is obviated by employing a pair of small brackets 82 and 83 for rigidly clamping the magnet 81 against the off-10 set portions 30 of the pole pieces 74 and 75 in the manner best illustrated in Fig. 8. The complete field structure is securely mounted within the cup-shaped supporting member 48 by means comprising a pair of screws 84 and 85 which extend through openings in the brackets 82 and 15 83 and in the pole pieces 74 and 75 and are threaded into the bottom portion of the member 48.

It is advantageous to clamp rigidly with uniform force all points of the receiver cell diaphragm periphery and to stretch the diaphragm during the clamping operation, thereby to secure greater stiffness thereof. These results are attained by providing spring means in the form 20 of a dished spring 86 which cooperates with the two members 48 and 47 to clamp the diaphragm 51 at its outer periphery against the upper edge of the cup-shaped member 48. This spring 86 rests in an outwardly tapering groove provided 25 in the bottom of the cupped clamping member 47 and is so arranged that its outer edge projects beyond the outer edge of the groove to engage resiliently the adjacent surface of the diaphragm 51 during the clamping operation. Thus, as the 30 member 47 is screwed onto the member 48 the extreme outer edge of the spring 86 comes in contact with the adjacent surface of the diaphragm 51 to exert a substantially uniform clamping pressure on the periphery of the diaphragm at all points thereof. Additional clamping 35 pressure causes the outer peripheral edge of the dished spring to flatten with the result that it expands slightly in a radial direction and exerts a decided stretching force on the diaphragm 51. This force artificially enhances the stiffness 40 of the diaphragm with the resulting advantage of improving its frequency response characteristic.

The arrangement for clamping uniformly the 50 diaphragm to the associated supporting member and for stretching the diaphragm described above is disclosed and claimed in applicant's pending application, Serial No. 165,257, filed September 23, 1937, which is a division of this application.

While there has been described what is at present considered to be the preferred embodiment of the invention it will be understood that various modifications may be made therein without departing from the invention and it is contemplated, therefore, in the appended claims to cover all such modifications as fall within the true spirit and scope of the invention.

1. A telephone hand set comprising transmitter 65 and receiver cups each including contact members, self-contained transmitter and receiver cells each including contact members for individually engaging the corresponding contact members of the corresponding cup, ear and 70 mouth pieces associated with corresponding ones of said cells, means for securing each of said cells in assembled relation and in its corresponding cup independently of the corresponding one of said pieces associated therewith and in a position such that the associated contact members

are in firm engagement, and means for securing each of said pieces to its corresponding cup.

2. A telephone hand set comprising transmitter and receiver cups each including contact members, self-contained transmitter and receiver cells each including contact members for individually engaging the corresponding contact members of the corresponding cup, ear and mouth pieces associated with corresponding ones of said cells, means for securing each of said cells in assembled relation and in its corresponding cup independently of the corresponding one of said pieces associated therewith and in a position such that the associated contact members are in firm engagement, means for securing each of said pieces to its corresponding cup, said last-named means each including a member requiring a special tool to actuate the same to remove the corresponding piece but being incidentally actuatable when the corresponding piece is moved in one direction relative to the corresponding cup, and locking means for preventing such relative movement.

3. A telephone hand set comprising a cup constructed of insulating material, an annular member rigidly secured to said cup and having a portion threaded along one of its peripheral edges, a telephone instrument cell comprising a pair of supporting members provided with interengaging threads for assembling said cell, the threads of one of said last-named members engaging with the threads of said annular member to secure said cell to said cup, a member constructed of insulating material and provided with a cupped portion for surrounding the portion of said cell extending outside said cup, and means for securing said last-named member to said cell, said means comprising a threaded portion of one of the supporting members of said cell and an additional member provided with threads engaging the threaded portion of said one of said cell members, said additional member being so constructed as to require a special tool for unscrewing the same to remove said member constructed of insulating material from the hand set assembly.

4. A telephone hand set comprising a cup constructed of insulating material, an annular member rigidly secured to said cup and having a portion threaded along one of its peripheral edges, a telephone instrument cell comprising a pair of supporting members provided with interengaging threads for assembling said cell, the threads of one of said last-named members engaging with the threads of said annular member to secure said cell to said cup, a member constructed of insulating material and provided with a cupped portion for surrounding the portion of said cell extending outside said cup, means for securing said last-named member to said cell, said means comprising a threaded portion of one of said supporting members of said cell and an additional member provided with threads engaging the threaded portion of said one of said cell members, said additional member being so constructed as to require a special tool for unscrewing the same to remove said member constructed of insulating material from the hand set assembly, and means for preventing relative rotary movement between said cup and the member of insulating material, whereby said additional member is prevented from being unscrewed except through the use of said special tool.

5. A telephone instrument assembly comprising a cup constructed of insulating material, a telephone instrument cell rigidly mounted at least

partially within said cup, a member constructed of insulating material and cooperating with said cup to surround said cell, means for securing said member to said cell, said means comprising a 5 threaded portion of said cell and an additional member provided with threads engaging the threaded portion of said cell, said additional member being so constructed as to require a special tool for unscrewing the same to remove-
10 said member constructed of insulating material from the telephone instrument assembly.

6. A telephone instrument assembly comprising a cup constructed of insulating material, a telephone instrument cell rigidly mounted partially 15 within said cup, a member constructed of insulating material and having a cupped portion surrounding the portion of said cell extending out-

side said cup, means for securing said member to said cell, said means comprising a threaded portion of said cell and an additional member provided with threads engaging the threaded portion of said cell, said additional member being so constructed as to require a special tool for unscrewing the same to remove said member constructed of insulating material from the telephone instrument assembly, and means comprising interlocking portions of said cup and said member constructed of insulating material for preventing relative rotary movement between said cup and said member constructed of insulating material, whereby said additional member is prevented from being unscrewed except through the use 10 of said special tool. 15

HAROLD C. PYE.
